REGENERATOR

Nicholas F. Egler, Monessen, Pa.

Application January 10, 1933, Serial No. 650,977

8 Claims. (Cl. 263—15)

The invention relates to regenerators for open-hearth furnaces. It has been found—for reasons with which this invention is not directly concerned—that in the operation of open-hearth furnaces of preferred size and capacity a plurality of regenerator units for the air is advantageous.

And it has been found that in the use of such a plurality of regenerator units a tandem arrangement, in which the whole stream of outgoing gases (at one end of the furnace) and the whole stream of entering air (at the other end) traverses the units in succession, is, from the point of view of efficiency, superior to a parallel arrangement, in which one portion of the divided stream traverses one chamber and another portion another chamber. But in the tandem arrangement the erosion of the stream of outflowing gases upon the checkerwork in the regenerator units—and, particularly, in the first unit of the succession—is so great that the otherwise preferable arrangement has been abandoned, in favor of the inferior parallel arrangement.

I have discovered an arrangement of structure and a consequent method of operation which under normal conditions of draft (otherwise established), while it affords successful (and, indeed, improved) regeneration, so far distributes the reduction in the rate of flow that in the first unit erosion is reduced and brought within practicable limits.

In the tandem scheme as it heretofore has been projected the regenerator units are arranged in end-to-end succession in the direction of flow of the stream of gas; so that (qualified only by such subdivision and lateral spread of the stream as are incident to passage through checkerwork) the stream deviates from a straight-line course only by turns in one plane—ordinarily the vertical plane.

Through experimentation and observation I have discovered that by arranging the tandem units side by side instead of end to end, in addition to the subdivision and lateral spread incident to regeneration, the stream is turned from the plane first indicated; it is diverted in a third dimension. The totality of the stream (speaking in specific terms of ordinary installation) is caused to follow not merely a vertically deviating course, but a course that deviates both vertically and laterally. Such third-dimensional meandering, I have found, imposes such check on the rate of flow that, with the successful (and, indeed, superior) regeneration, erosion is reduced and the scheme becomes practicable.

A regenerator which embodies the structure and admits of practice of the method of my invention is shown in the accompanying drawings. Fig. I is a view in horizontal section through the regenerator and adjacent portions 60 of the gas passageways; Fig. II is a view of the regenerator in vertical, longitudinal section, and to smaller scale, taken on the plane II—II of Fig. I; Fig. III is a view of the regenerator in vertical cross-section, taken on the plane III—65 III of Fig. I. And Fig. IV is a fragmentary view, comparable with Fig. II, showing to smaller scale a modification in structure.

The regenerator installation includes a checker chamber 1 which is divided longitudinally by a 70 partition 2, providing two compartments 3 and 4. The walls of the chamber 1 are constructed of refractory masonry, externally braced and reinforced by structural steel, according to usual practice. The compartments 3 and 4 are each elongate in horizontal section (cf. Fig. I); compartment 3 is of greater horizontal area than compartment 4, and both compartments are provided with refractory checkerwork 5. The partition 2 extends upward from the floor of the checker 75 chamber, separating the checkerwork in the two compartments 3, 4. It is important to note that the bodies of checkerwork in the two compartments are built an interval above the floor of the chamber 1, so that passages 6 are provided beneath checkerwork in chamber 3, and passageways 7 beneath the checkerwork in chamber 4. The passages 6 and passageways 7 extend lengthwise of the respective chambers 3, 4 and parallel to the partition 2, and presently the advantages 80 of this structure will be elaborated. In Fig. III it will be observed that the checkerwork 5 and the partition 2 terminate at an interval below the roof of the chamber 1. Thus, the two checker compartments are in communication above, and 85 90 gases may flow transversely over the partition 2, leaving the top of the checkerwork in one compartment and entering the top of the checkerwork in the other compartment.

At one end of the checker chamber 1, I provide 100 a slag-pocket 8, and, according to usual practice, a conduit 9 (Fig. II) extends from the furnace (not shown) and opens into the slag-pocket. It will be perceived that the slag-pocket extends an appreciable distance below the floor of chamber 1. 105 The gases coming from the furnace by way of conduit 9 enter the slag-pocket, whence they flow into the passages 6 which open through the end wall 1a of the checker chamber. The communication between the slag-pocket and the passages 110

6 is established through an orifice 10 formed in the wall of the checker chamber a substantial interval above the floor of the slag-pocket. The passages 6 also open through the opposite end 5 wall 1b of the checker chamber, and, by means of a port 11, the passages 6 are adapted to communicate with the flues 12 which extend to the usual reversing valves (not shown) of the furnace. The port 11 is provided with a closure 13, so that communication between the passages 6 and the flues 12 is at the command of the furnace operator. In passing, I may mention that the above-described regenerator structure, slag-pocket, and flues 12 are provided at each of the opposite ends 15 of the furnace. During operation of the furnace, the reversing valves are so adjusted that, at the outgo end of the furnace, the flues 12 communicate with the stack, and, accordingly, constitute stack flues, while at the intake end of the furnace, 20 duplicate flues 12 in communication with the air supply serve to admit air to the regenerator.

The passageways 7, extending beneath the checkerwork in compartment 4, open through the wall 1b of the checker chamber, at the end of the chamber opposite the slag-pocket 8. It will be understood, therefore, that (slide 13 being closed) the waste gases enter the checker chamber 1 at one end and to one side of the partition 2, and leave the checker chamber by way of an opening 30 located at the opposite end and to the opposite side of the partition 2; and that in their course the waste gases flow through both of the two bodies of checkerwork: first upwardly through the body in chamber 3, then above partition 2, and 35 then downwardly through the body in chamber 4.

Upon leaving the outgo end of the furnace, the hot waste gases pass through conduit 9 and enter the slag-pocket 8 in its upper portion. The slag-pocket is of relatively large internal dimensions, 40 so that the waste gases expand, upon leaving the conduit 9. Such expansion arrests the flow of the gases in the slag-pocket, and the slag and dust particles (which are always entrained with the hot waste gases of an open-hearth furnace) are freed to settle upon the bottom of the slag-pocket. 45 Upon entering the slag-pocket, the waste gases flow in the general paths indicated by the arrows in Fig. II, and flow into the passages 6 beneath the checkerwork in the larger of the several (in this case I show two) checker compartments of 50 the regenerator. The effective horizontal area of the larger checker compartment—the compartment 3—is at least fifty per cent. greater than the corresponding area of the smaller compartment 4. It is exceedingly important that the hot 55 waste gases shall, upon leaving the slag-pocket, enter beneath the checkerwork in the largest of the several compartments in the regenerator. The waste gases entering the passages 6 flow in streams running parallel to the partition 2. The 60 elongate passages 6 tend to insure an even distribution of hot gases beneath the checkerwork, so that all vertical ways 14 in the checkerwork are supplied with streams of gases, and localized 65 overheating of the checkerwork prevented.

Contrary to the concern of others, I do not 70 specifically attempt to keep the slag, included with the hot waste gases, in a molten condition. Indeed, I endeavor to insure that so much of the included slag and dust particles as are carried over into the passages 6 from the slag-pocket shall be in a substantially solid state, so that the 75 particles may settle loosely upon the floor of the checker chamber. In first passing and guiding the waste gases beneath the checkerwork of the

larger compartment, I obtain at least two essential advantages:

(1) The waste gases, while they are still in practically their hottest condition, are spread uniformly beneath the checkerwork in the compartment of the largest effective area. Thus I minimize any tendency for one region of the checkerwork to receive more gases and heat than another, and accordingly the whole checkerwork is better adapted to withstand the intense heat of the waste gases. 80 85

(2) By distributing and expanding the waste gases beneath a large area of checkerwork, the streams of gases must necessarily make abrupt turns, and flow in angularly extending conduits as they enter the vertical ways 14 in the checkerwork. The streams of gases in making these abrupt turns give up practically all of their included slag and dust particles, so that, upon emerging from the top of the checkerwork in compartment 3, the gases are substantially cleansed. The freed slag and dust accumulate in loose condition upon the floor of the checker compartment 3. The other checker compartment 4 remains clean for long campaigns of furnace 100 operation, and the furnace operator need only be concerned with removal of accumulated slag and dust from the slag pocket 8 and passages 6. 90 95

While rising through the checkerwork in compartment 3, the waste gases transfer to the checkerwork large quantities of their heat. Upon reaching the top of compartment 3, the gases flow laterally of the checker chamber 1 (Fig. III), across the partition 2, and enter the top of the checkerwork in the smaller compartment 4. The 105 cleansed waste gases, due to the suction created in the system by the usual fan or stack, are drawn downward through the checkerwork, and enter the passageways 7. In flowing through the checkerwork in compartment 4, the waste gases 110 give up much of the residue of their heat, and so provide the smaller of the two checker compartments with a store of heat at lower temperature than the store of heat in the larger compartment. The passageways 7, as above mentioned, extend beneath the checkerwork, and throughout the length of the compartment 4. The waste gases enter the passageways 7 at points along the entire length of the compartment 4, whence they flow in streams running parallel to 115 the partition 2. Upon streaming to the ends of passages 7, the gases enter the stack flues 12, whence they are ultimately discharged into the open atmosphere. Thus, upon entering the passages 6, the gases in their totality turn upward 120 and pass in vertical plane through checker compartment 3; at the top of compartment 3 the gases flow laterally of the plane of their ascent, and pass downward in vertical plane, through the compartment 4, and into the passageways 7, 125 130 wherein the course of the gases extends in a horizontal plane. That is to say, in my structure, I cause the waste gases, in addition to such spreading as is incident to flow through the checkerwork, to describe a meandering, three-dimensional course. 135 140

When the furnace is reversed, and the regenerator becomes the air preheater, the flues 12 become air ducts, conveying cold air from the atmosphere to the checker chambers. The air enters passageways 7, flows upward through compartment 4 and downward through compartment 3, whence in highly heated condition it enters the passages 6. From passages 6, the air is conducted to the furnace in accordance with usual practice. 145 150

It may be remarked that in my regenerator, the cold air first enters the smaller of the checker compartments, which also is the compartment whose checkers are preheated to the lower temperature. Accordingly, the air receives a primary preheating in compartment 4; this primary preheating effects, of course, an expansion of the air. The increased volume of air is readily accommodated by the checkers in the larger, hotter compartment 3. Upon flowing downward through the checkers in compartment 3, the air is subjected to further preheating. This additional or secondary preheating, in the larger compartment 3, boosts the temperature of the air so that in largest measure the available heat in the products of combustion of the furnace (stored in the checkerwork) is transferred to the air for combustion.

My invention includes structural organization which permits the accumulations of slag and dust to be removed from the passages 6, without closing and cooling down the structure. More specifically, the wall 8a of the slag-pocket is provided with a door 15 which is so located with respect to the passages 6 that, upon opening the door, a jet of steam or compressed air may be directed along passages 6, to clean away the accumulations of dust and slag. Before the jet is brought into play, however, the closure in port 11 is withdrawn, as in Fig. I it is shown to be, and thus the passages 6 are brought into direct communication with the stack flues 12. Thereupon, a jet 150 of steam or compressed air (Fig. IV) is directed through the door 15 and along the passages 6, and the accumulations on the floor of the passages are blown into the stack flues 12, whence they are drawn into the stack and discharged. It will be understood, of course, that the passages 6 are only cleaned when the reversing valves of the furnace are so adjusted that the regenerator to be cleaned is connected to the stack of the furnace. It will also be manifest that the closure 13 remains in closed position across the port 11, during the normal operation of the regenerator, and is opened only when the passages 6 are to be cleaned. In opening the closure 13, the draft of the stack becomes directly effective in the passages 6, and aids the jet in dislodging and removing the accumulated dust and slag. I contemplate, additionally, that the floor of the checker chamber 1 may be sloped in its extent from right to left (Fig. IV), to the end that any slag entering the passages 6 in liquid condition may flow down the sloping floor and return to the slag-pocket 8.

I claim as my invention:

1. A regenerator for a reversing furnace including two units of checkerwork arranged side by side, separated by a wall of refractory masonry, and laterally interconnected above for tandem operation, the said units being adapted to receive and deliver a stream of gas in relatively elongate courses that extend side by side and in parallelism and to permit flow from one unit to the other in a course transverse to the courses of reception and delivery.

2. A regenerator for a reversing furnace including two units of checkerwork arranged side by side, and provided severally beneath with longitudinally-extending passageways for reception and delivery of a stream of gas, the passageway beneath at least one of said units being divided into a plurality of relatively elongate passages, said regenerator being provided above with a transversely-extending passageway for the ad-

vance of the stream of gas from one of said units to the other, whereby the stream progressing through the two units in tandem course, in addition to the meanderings of fractional parts, incident to progress through checkerwork, is caused in its totality to take a meandering three-dimensional course in the regenerator.

3. A regenerator installation for a reversing furnace, including the combination of a slag pocket, a conduit extending from said furnace to said slag pocket, a checker chamber, a partition dividing said chamber into two checker compartments of unequal horizontal areas, a passage extending beneath the checkerwork in the larger of said compartments, which passage communicates with said slag pocket and opens through the wall of said chamber at such region that waste gases advancing through the slag pocket from the furnace flow into the passage in streams running substantially parallel to said partition, said partition terminating beneath the roof of said chamber, whereby, upon moving upward through the larger checker compartment, the waste gases flow transversely of the chamber and enter the smaller of said checker compartments, a stack flue, and a passageway extending beneath the checkerwork in the smaller of said compartments, which passageway communicates with said stack flue and opens through the wall of said chamber at such region that the waste gases, upon moving downward through the checkerwork of such smaller compartment, flow through said passageway in streams running substantially parallel to said partition.

4. A regenerator installation for a reversing furnace, including the combination of a slag pocket, a conduit extending from said furnace to said slag pocket, a substantially rectangular checker chamber, a partition dividing said chamber into two checker compartments of unequal horizontal areas, said partition terminating beneath the roof of said chamber, whereby gaseous flow may progress transversely of the chamber from the top of one checker compartment to the top of the other checker compartment, a passage extending beneath the checkerwork in the larger of said compartments, which passage opens through the wall of said chamber adjacent one end and to one side of said partition and communicates with said slag pocket, a stack flue, and a passageway extending beneath the checkerwork in the smaller of said compartments, which passageway opens through the wall of said chamber adjacent the other end and to the other side of said partition and communicates with said stack flue.

5. A regenerator installation for a reversing furnace, including the combination of a slag pocket, a conduit extending from said furnace to said slag pocket, a checker chamber, a partition extending longitudinally of said chamber and dividing it into two elongate checker compartments, a passage extending from said slag pocket and opening through the wall at one end of the first of said elongate compartments, said passage being so disposed that waste gases advancing from the furnace sweep beneath the checkerwork in said compartment in streams that are substantially parallel to said partition, said two compartments being in direct communication adjacent the top of said partition, a stack flue, and a passageway extending from said stack flue to one end of the second of said elongate compartments, which passageway is so disposed that waste gases leaving the second compartment sweep beneath

its checkerwork in streams that are substantially parallel to said partition.

6. A regenerator installation for a reversing furnace, including the combination of a slag pocket, a conduit extending from said furnace to said slag pocket, two checker compartments arranged side by side, one compartment being of substantially greater effective area than the other, a passage opening through the wall of the larger of said compartments adjacent one end of the regenerator and communicating with said slag pocket, said passage being so disposed that waste gases advancing through the slag pocket from the furnace sweep beneath the checkerwork in said larger compartment, a top passage between said two compartments, whereby, upon rising through the checkerwork of the larger of said compartments, the waste gases enter the top of the smaller of said compartments, a stack flue, and a passageway extending from beneath the checkerwork in said smaller compartment and communicating adjacent the opposite end of the regenerator with said stack flue.

7. A regenerator installation for a reversing furnace, including the combination of a slag pocket, a conduit extending from said furnace to said slag pocket, two checker compartments, one compartment being of substantially greater effective area than the other, a passage extending beneath the checkerwork in the larger of said compartments and opening through one end wall of the compartment into said slag pocket, whereby

waste gases advancing through the slag pocket from the furnace sweep beneath the checkerwork in said larger compartment, a stack flue, a port in the opposite end wall of said compartment affording communication between said passage and said flue, a closure for said port, and a door in the wall of said slag pocket, which door is so located with respect to said passage that steam or air jets may be directed into said passage to blow slag and dust accumulations into said flue; a top passage between said two checker compartments, whereby, upon rising through the checkerwork of the larger of said compartments, the waste gases enter the top of the smaller of said compartments, a passageway extending from beneath the checkerwork in said smaller compartment to said stack flue.

8. A regenerator installation for a reversing furnace, including the combination of a slag pocket, a conduit extending from said furnace to said slag pocket, a checker chamber, a passage beneath the checkerwork in said chamber communicating at one end with said slag pocket, a stack flue, a port at the opposite end of said passage adapted to establish communication between said passage and said flue, a closure for said port, and a door in the wall of said slag pocket, which door is so located with respect to said passage that dust-removing jets of air or steam may be directed along said passage and toward the port opening into said flue.
